UNITED STATES PATENT OFFICE.

HENRY ROSE, OF GAINSBOROUGH, ENGLAND.

APPARATUS FOR FEEDING ARTICLES TO WRAPPING MECHANISMS.

972,649.

Specification of Letters Patent. Patented Oct. 11, 1910.

Application filed September 9, 1910. Serial No. 581,142.

To all whom it may concern:

Be it known that I, HENRY ROSE, a subject of the King of Great Britain and Ireland, of Albion Works, Gainsborough, in the 5 county of Lincoln, England, have invented new and useful Improvements in Apparatus for Feeding Articles to Wrapping Mechanism, of which the following is a specification.

10 This invention relates to the apparatus (described in the specification to British Letters Patent No. 27722/07) and consists in providing simple and efficient means whereby a series of two or more articles can 15 be fed to such a machine for the purpose of wrapping each series together so as to form one package.

The apparatus comprises an improved form of magazine having a sideway opening 20 at the bottom thereof, of a height or which is capable of being adjusted to a height corresponding to the number of articles to be wrapped together and a pusher adapted to reciprocate so as to push out the requisite 25 number of articles sidewise the articles above those being expelled being supported by means to be hereinafter described, and thereafter being allowed to descend so as to occupy the position vacated by the expelled 30 articles.

I will describe the invention with reference to the accompanying drawings on which—

Figures 1 and 2 are elevations at right angles to each other showing one modification and Figs. 3 and 4 are similar views and Fig. 5 is a plan of the upper side of another modification.

The apparatus for the purpose aforesaid 40 comprises as shown in the accompanying drawings an upright magazine 54 in which the boxes α to be wrapped are placed. The upright magazine is provided at two opposite sides at bottom with a sideway opening 45 55 of a height in accordance with the number of boxes to be packed together by the apparatus to which they are fed. Capable of working through these openings 55 is a pusher 56 slideable upon the bed plate 57 of 50 the magazine 54 which pusher 56 will, at each reciprocation, push the desired number 55 of boxes α out sidewise and expel them simultaneously from the magazine 54. The pusher 56 is operated by any suitable mechanism which is shown in the said figures as consisting of a lever 58 centered at 59 and

connected by a link 60 to the pusher 56 and operated in one direction by a cam 61 acting on a roller 62, carried by the lever 58, and in the other direction by a spring 63. Means 60 are also provided by which the pile of boxes α above those being expelled are supported while the pusher 56 is operating. Where the number of boxes α to be expelled at each operation is small, or the said boxes are 65 light, this supporting device may be such as will support the pile of boxes α by bearing upon the box which is next above the series being expelled, and when this is released, the pile will descend by gravity to bring a 70 fresh number of boxes into position for being expelled. The mechanism for this purpose is shown in Figs. 1 and 2 of the accompanying drawings as consisting of a lever 75 64 centered at 65 which lever is pressed inward by a spring 66 and provided with a roller 67 and nose-piece 68. When the pusher 56 is expelling the boxes, the spring 66, will cause the nose-piece 68 to come in contact with the lowermost box in the magazine 54, to retain the pile of boxes α above, and the rear-part of the pusher 56, on its return movement, will act upon the lever 64 and remove the nose-piece 68 from its retaining position and allow the pile of boxes 80 α in the magazine 54 to descend.

In cases where the number of boxes α required to be expelled at each operation is large, or they are not light, and the extent to which they would have to fall would 90 render them liable to become displaced, it is preferred to use a support which operates from beneath and is actuated so that it rises as soon as the pusher has pushed the required number of boxes sufficiently to allow 95 the said support to reach what is then the lowermost box in the magazine 54, this support being afterward lowered so as to allow the boxes α in the magazine to descend, while resting on the said support so as not to 100 become liable to be displaced. A convenient arrangement is illustrated in Figs. 3, 4, and 5 of the accompanying drawings.

The pusher 56 is made in such form, for instance, in the form of a frame, that it will 105 allow the support 69 to rise while the pusher is in operation.

The support 69 is connected by a cross-piece 70 with a rod 71 and the said support 69 and rod 71 can slide in guides 72 and 73, 110 respectively.

74 is a roller which runs upon a cam 75,

which will give the required rising movements to the support 69 and allow it and the boxes resting upon it (assisted by a spring 76 if desired) to descend gently. The boxes 5 *z* in the required number to form each package, or parcel, are carried to the apparatus which wraps them together by means of a suitable feeding device.

The parts of the apparatus which I 10 have not described are arranged and operated in accordance with the specification of my aforesaid British Letters Patent No. 27,722 A. D. 1907. By the combination of the improvements according to my present 15 invention with the machine in accordance with my aforesaid British patent, a machine is provided which is more efficient in its operations of cementing, feeding, and folding, and which labels, or wraps, the boxes, or the 20 like in a better manner.

What I claim is:—

1. In apparatus of the character described, the combination of an upright magazine containing a column of articles, said magazine having a side delivery opening in the lower portion, a reciprocating pusher operable through said opening to segregate a series of the articles from the column and deliver the same through said opening, and 25 means engaging the lowermost article remaining in the column for supporting the column of articles against the action of gravity above those being expelled, said means including a member having a portion 30 to enter the magazine, and a cam-actuated mechanism for operating said member.

2. In apparatus of the character described, the combination with an upright magazine containing a column of articles and having a side delivery opening, and a pusher operable therethrough to expel a series of articles, of a support and means for operating the same in an upward direction while the pusher is expelling the articles, whereby the articles in the magazine above the pusher 40 will be supported, said means allowing the support to be lowered to position another series of articles in the range of action of the pusher.

3. In apparatus of the character described, 50 the combination with an upright magazine containing a column of articles, and having a side delivery opening, and a pusher operable therethrough to expel a series of articles, of means for supporting the column 55 of articles while a series of said articles is being expelled, said means including a vertically-disposed reciprocating supporting member, and means engaging the same to cause it to ascend and support the column 60 of articles while the pusher is expelling a series of the articles and to descend and lower the column of articles to bring a new series of articles into the range of action of the pusher.

In testimony whereof I have signed my name to this specification, in the presence of two subscribing witnesses.

HENRY ROSE.
